UNITED STATES PATENT OFFICE.

FRANZ MEYER, OF NEW YORK, N. Y.

MUFFLE ROASTING-FURNACE.

SPECIFICATION forming part of Letters Patent No. 761,691, dated June 7, 1904.

Application filed September 1, 1903. Serial No. 171,493. (No model.)

To all whom it may concern:

Be it known that I, FRANZ MEYER, a subject of the Emperor of Germany, residing in the city, county, and State of New York, have invented certain new and useful Improvements in Muffle Roasting-Furnaces; and I do hereby declare the following to be a full, clear, and exact description of the invention, such as will enable others skilled in the art to which it applies to make and use the same.

My present invention, which is subsidiary to my Patent No. 731,114, dated June 16, 1903, relates to muffle roasting-furnaces, and has for its object to provide a furnace comprising a series of roasting-chambers each formed as a separate unitary structure, effectively braced and anchored against the disrupting effects of expansion by means of an inclosing metallic shell lined with refractory material, a heating-furnace common to the series of chambers, suitable flue connections, preferably having expansion-joints between the successive units or chambers of the series, and means for preheating the air for oxidizing the sulfur in the ore.

The invention is illustrated in the accompanying drawings, in which—

Figure 1 is a vertical section through a muffle-furnace comprising three units or roasting-chambers. Fig. 2 is a transverse vertical section through a single unit. Fig. 3 is a horizontal section on the line 3-3 of Fig. 1.

In my former patent, above referred to, is shown a horizontal series of roasting-chambers connected to form a unitary structure of brick or masonry, with continuous inclosing walls embracing the entire apparatus. The present invention is designed to relieve and distribute such expansion and contraction strains as are incident to this construction, so that they may be divided up and absorbed among several independent elastic chambers or units.

Referring to the drawings, the numeral 1 indicates a series of roasting chambers or furnaces arranged in a horizontal row upon a basal foundation or support, which chambers are designed to be heated by a common fur-

nace or equivalent source of heat. Each 50 chamber forms a separate distinct unit in the series, and the several units are so connected as to be supplied with heat from said common furnace. In the preferred form of the invention each unit 1 comprises an outer casing 2, 55 of metal, preferably a sectional cylinder or shell of iron or steel, embracing a lining 3, of fire-brick or other refractory material. Each chamber is divided into a plurality of superposed roasting-hearths 5, beneath the lower 60 two of which are heating chambers or flues 4 and 8, respectively, said heating-chambers being connected at the end of the series of roasting-chambers 11 by a vertical flue 4'. The roasting-hearths 5 are provided with rotary stirrers 6, mounted upon columns 7, passing vertically through the several hearths in each roasting-chamber, and the material fed from hoppers 12 to the upper hearths is discharged from one hearth to the next below by way of peripheral and central openings in alternate hearths, so that the roasting ore passes from one hearth to the next lower of the series in the respective furnaces to suitable discharge-outlets 20 in the lowermost 75 hearth of each series. The stirrer-columns and rabble-arms are preferably formed of seamless drawn-steel tubes, the rabble-teeth, which are of cast-iron, being secured to the arms in any preferred manner. The columns 80 and arms are cooled by drawing or forcing air or water through the hollow tubes according to any of the approved methods.

Heating-furnaces 1111, located at the lower forward end of the structure, constitute a 85 common source of heat for all of the roasting-chambers, an arrangement that effects a uniform and efficient roasting operation, while it also subserves a material economy in fuel consumption. The products of combustion 90 from furnaces 1111 pass into flues or chambers 44 below the lower roasting-hearth 5 of each unit 1. The respective chambers 4 of each unit are connected by flues 13, which are constructed to provide a suitable joint to 95 allow for the expansion and contraction of the units and preserve a gas-tight connection between the units. Each flue 13 consists of

telescoping rims or projections 14 15, formed as continuations of the metal shells 2 2 of adjacent units lined with fire-brick or other refractory material. The space between the 5 abutting ends of the flue-linings is filled with fire-clay or other loose refractory material that will ordinarily preserve an efficient seal at the joint and yet be sufficiently yielding to work out when the joint expands unduly. 10 The heating-chambers 8 of each of the units are also connected by flues 13, each formed with an expansion-joint in substantially the same manner as the corresponding flues connecting the lower heating-chambers 4 4—viz., 15 with telescoping rims 14 and 15, lined with fire-brick and sealed or luted with fire-clay 16. After traversing the several heating-chambers 4 and 8 in series the products of combustion are discharged by way of stacks 25. 20 In order to preheat the air which is admitted in regulable quantities to the roasting-chambers for the purpose of oxidizing the sulfur in the roasting ore, a suitable duct 21 is formed in the bottom and side wall of each 25 hearth, through which duct the air is drawn and discharged in a highly-heated condition by way of suitable openings 22 into the lowermost hearth of each roasting-chamber.

As the ore is fed to the respective roasting-chambers from hoppers 12 it is subjected to 30 a preliminary roasting in the upper hearth, from which it is forced by the rabbles 6, by way of peripheral openings 9, to the intermediate hearth, which is directly heated by the 35 hot gases in subjacent chamber 8. The ore then drops through the central opening 10 upon the lowermost hearth, where it is subjected to the heat from chambers 4 and 8 and to the highly-heated air from duct 21, after 40 which said ore is discharged at outlet 20. The heating-gases pass from furnaces 11 through chambers 4 4 in series, highly heating the lower hearths 5 from below, thence by vertical flue 4' to chambers 8 8, which are 45 traversed successively by the hot gases on the way to stacks 25. As the individual roasting-chambers or units 1 are subjected to the high heat of the burning gases they are free to expand in all directions, and as the walls 50 are confined within the metal casings 2 breaking or cracking of the structure is avoided. As the sides of adjacent units approach each other the flues 13, by reason of the telescoping joints therein, preserve a proper and efficient 55 connection between the respective heating-chambers.

Having thus described my invention, what I claim is—

1. A roasting-furnace, comprising a series 60 of roasting-chambers separated by intervening spaces, a heating-furnace common to the series, and flues for the heating-gas connecting with the heating-furnace at one end and

the stack at the other through the successive chambers; substantially as described. 65

2. A roasting-furnace, comprising a series of separate units, each consisting of a metal shell and a refractory lining, a heating-furnace common to the series, and flues for the heating-gas connecting with the heating-furnace 70 at one end and the stack at the other through the successive units; substantially as described.

3. A roasting-furnace, comprising a series of separate units, each made up of a series of superposed hearths, a metal shell and a refractory lining, a heating-furnace common to the series, and flues connecting with the heating-furnace at one end and the stack at the other through the successive units; substantially as 75 described. 80

4. A roasting-furnace, consisting of a row of separate chambers, each formed as a unit, comprising a metal shell, a refractory lining therefor, a series of superposed hearths, and heating-chambers below said hearths, a heating-furnace common to the series, and flues connecting with the heating-furnace at one end and the stack at the other through the heating-chambers of the successive units; substantially as described. 90

5. A roasting-furnace, comprising a series of separate units, a heating-furnace common to the series, flues connecting with the heating-furnace at one end and the stack at the other through the series of units, and expansible flue connections between successive units; substantially as described. 95

6. A roasting-furnace, comprising a series of separate units, each consisting of a metal shell and a refractory lining, a heating-furnace common to the series, and flues for the heating-gas connecting with the heating-furnace at one end and the stack at the other through the successive units and flue connections between adjacent units, each of said flue connections comprising lateral telescoping sections of the shells of adjacent units; substantially as described. 100 105

7. A roasting-furnace, comprising a series of separate units, each consisting of a metal shell and a refractory lining, a heating-furnace common to the series, and flues for the heating-gas connecting the successive units, each of said flues comprising lateral telescoping sections of the shells of adjacent units, a refractory lining for said telescoping sections, and a suitable luting between the abutting edges of the refractory lining; substantially as described. 110 115

In testimony whereof I affix my signature in 120 presence of two witnesses.

FRANZ MEYER.
